US0D1069312S

(12) **United States Design Patent** (10) **Patent No.:** **US D1,069,312 S**
(45) **Date of Patent:** **** Apr. 1, 2025**

(54) **CONVEYOR BELT MODULE**

(71) Applicant: **Laitram, L.L.C.**, Harahan, LA (US)
(72) Inventors: **Gilbert J. MacLachlan**, Harahan, LA (US); **David Aaron van Schalkwijk**, Metairie, LA (US); **Adam E. Bannerman**, Mandeville, LA (US)
(73) Assignee: **Laitram, L.L.C.**, Harahan, LA (US)
(**) Term: **15 Years**
(21) Appl. No.: **29/785,847**
(22) Filed: **May 27, 2021**
(51) LOC (15) Cl. 12-05
(52) U.S. Cl. USPC D34/29
(58) **Field of Classification Search**
USPC D34/29
CPC B65G 17/10; B65G 17/30; B65G 17/46
See application file for complete search history.

(57) **CLAIM**

The ornamental design for a conveyor belt module, as shown and described.

DESCRIPTION

FIG. 1 is a top isometric view of a conveyor belt module according to the present invention.

FIG. 2 is a bottom isometric view of the conveyor belt module of FIG. 1.

FIG. 3 is a bottom view of the conveyor belt module of FIG. 1.

FIG. 4 is a top view of the conveyor belt module of FIG. 1.

FIG. 5 is a first side enlarged view of the conveyor belt module of FIG. 1.

FIG. 6 is a second side enlarged view of the conveyor belt module of FIG. 1.

FIG. 7 is a front view of the conveyor belt module of FIG. 1; and,

FIG. 8 is a rear view of the conveyor belt module of FIG. 1. The broken lines in the figures are to show portions of the conveyor belt module which are not part of the claimed design.

1 Claim, 5 Drawing Sheets
